ATTORNEYS

Patented Feb. 27, 1923.

1,447,000

UNITED STATES PATENT OFFICE.

FRANK H. WILSON, OF KALAMAZOO, MICHIGAN.

PUNCH.

Application filed February 4, 1922. Serial No. 534,107.

To all whom it may concern:

Be it known that I, FRANK H. WILSON, a citizen of the United States, residing at the city and county of Kalamazoo, State of Michigan, have invented certain new and useful Improvements in Punches, of which the following is a specification.

This invention relates to improvements in punches.

10 The main objects of this invention are:

First to provide an improved punch for the use of garage repair men and the like for punching gaskets and packings and other comparatively thin material.

15 Second, to provide a punch having these advantages providing various sized punches which may be very conveniently and rapidly operated, both in the matter of positioning the work and operating the punch, and one 20 which may be used to punch holes in sheets or parts of a large range of sizes.

Further objects, and objects relating to structural details, will definitely appear from the detailed description to follow.

25 I accomplish the objects of my invention by the devices and means described in the following specification. The invention is clearly defined and pointed out in the claims.

A structure which is a preferred embodiment of my invention is clearly illustrated 30 in the accompanying drawing, forming a part of this application, in which:

Fig. I is a side elevation of my improved punch.

35 Fig. II is a vertical transverse section on a line corresponding to line 2—2 of Fig. I, the punch being shown mainly in full lines.

In the drawing the base 1 is in the form 40 of a bar channeled on its under side at 2 for the escape of the punchings. An arm 3 overhangs the base, the arm being connected to the base at one end only, as at 4, the other end 5 being open for the introduction of work to the punches. The base has a 45 plurality of shouldered bores 6 therein providing upwardly facing seats 7 for the dies 8. The arm 3 has a plurality of cylindrical bosses 9 on its under side and cylindrical bosses 10 on its upper side. The sides 11 50 of the arm are beveled upwardly from the bosses 9, thus providing clearance or space for manipulation and adjusting of the work. The arm has a series of shouldered bores 12 aligned with the bores 6 and extending 55 through the bosses 9 and 10 providing guides for the punches 13.

These punches are shouldered at 14, the shoulders coacting with the shoulders 15 of the punch guides, thereby limiting the upward movement of the punches. The bores 60 6 are of such diameter that the punches can be introduced into their guides through these bores. The heads 16 of the punches are removably secured thereon by the pins 17. Coiled springs 18 are provided for re-65 tracting the punches, the lower ends of these springs being supported by the bosses 10. While their upper ends are supported by the cylindrical parts of the heads.

The punch is operated by striking the 70 heads with a hammer or the like and on thin material they may be operated by striking them with the hand. The work can be readily adjusted to the selected punch and the punch operated as stated. 75

My improved punch is especially designed for use in garages and the like where it is frequently desirable to punch holes of different sizes in gaskets, packings and the like, although it is desirable for use in various other relations. 80

I have illustrated a simple and practical embodiment of my improvements and have not attempted to illustrate or describe certain adaptations or modifications which I 85 contemplate as I believe the disclosure made will enable those skilled in the art to which my invention relates to embody or adapt the same as may be desired.

Having thus described my invention, what 90 I claim as new and desire to secure by Letters Patent, is:

1. In a punch, a body comprising a bar-like base and an overhanging arm spaced from said base and connected thereto at one 95 end only so that the work may be introduced between the arm and the base from the open end, said arm having cylindrical bosses on the top and bottom thereof and its under side being beveled from its said bosses, said 100 base having a plurality of shouldered bores therethrough providing upwardly facing die seats, said arm having shouldered bores extending through its said bosses and aligned with said die seat bores providing 105 punch guides, die members removably arranged in said die seats, shouldered punches provided with removable heads, said die seat bores being of a diameter permitting the introduction of the punches into the 110 punch guides therethrough when the punch heads are removed, and coiled retracting

springs for said punches disposed with their lower ends embracing said bosses on the top of said arm and their upper ends engaging said punch heads, said punch heads being sleeved upon the upper ends of said punches and having cylindrical parts fitting within and constituting supports for the upper ends of said springs.

2. In a punch, a body comprising a bar-like base and an overhanging arm spaced from said base and connected between the arm and the base from the open end, said base having a plurality of shouldered bores therethrough providing upwardly facing die seats, said arm having shouldered bores aligned with said die seat bores providing punch guides, die members removably arranged in said die seats, shouldered punches provided with removable heads, said die seat bores being of a diameter permitting the introduction of the punches into the punch guides therethrough when the punch heads are removed, and coiled retracting springs

for said punches resting on said arm and their upper ends engaging said punch heads. 25

3. In a punch, a body comprising a bar-like base and an overhanging arm spaced from said base and connected thereto at one end only so that the work may be introduced between the arm and the base from the open end, said arm having bosses on the top thereof, said base being provided with a plurality of dies, said arm having bores extending through its said bosses and aligned with said dies, punches arranged in said punch guides and provided with heads, and coiled retracting springs for said punches disposed with their lower ends embracing said bosses on the top of said arm and their upper ends engaging said punch heads, said punch heads having cylindrical parts fitting within and constituting supports for the upper ends of said springs. 40

In witness whereof, I have hereunto set my hand and seal.

FRANK H. WILSON. [L.S.]
